United States Patent Office

Des. 188,480
Patented July 26, 1960

188,480

PLASTIC COATED FABRIC OR SIMILAR ARTICLE

Jakob H. Vogel, West Orange, N.J., assignor to Inter-chemical Corporation, New York, N.Y., a corporation of Ohio

Filed Nov. 26, 1957, Ser. No. 48,673

Term of patent 14 years

(Cl. D87—3)

Figure 1 is a top plan view of a plastic coated fabric or similar article, showing my new design.

Fig. 2 is a side elevation view of coated fabric carrying applicant's claimed design and taken along the line 2—2 of Fig. 1.

I claim:

The ornamental design for plastic coated fabric or similar article, as shown.
